UNITED STATES PATENT OFFICE

ROSS E. LANGILL, OF MENOMINEE, MICHIGAN, AND WILLIAM B. GRUETER, OF MILWAUKEE, WISCONSIN, ASSIGNORS TO THE PRESCOTT COMPANY, OF MENOMINEE, MICHIGAN, A CORPORATION OF MICHIGAN

SAWMILL DOG

Original application filed September 16, 1925, Serial No. 56,590. Divided and this application filed August 1, 1931. Serial No. 554,520.

This invention relates to an improvement in sawmill dogs. The present application is a division of our pending application for sawmill dogs, filed September 16, 1925, Serial No. 56,590.

Sawmill dogs of the character of the present invention include upper and lower tongs supported for movement toward and away from each other in a vertical plane and also supported for movement transversely or in and out relative to the face of the knee of the sawmill carriage together with a motor organization for imparting the vertical and transverse movement to the dogs.

The object of the present invention is to provide a novel arrangement for guiding the tongs, especially the upper tong, for vertical movement in various adjustments transversely with respect to the knee face and also to provide a novel structural organization for shifting the upper and lower tongs in and out relative to the knee face under the power of the motor provided for this purpose.

Other objects and advantages reside in certain novel features of the construction, arrangement and combination of parts which will be hereinafter more fully described and particularly pointed out in the appended claims, reference being had to the accompanying drawings, forming a part of this specification, and in which:

Figure 1 is a view in side elevation showing a sawmill dog constructed in accordance with the present invention;

Figure 2 is a view in section taken on line 2-2 of Figure 1, and showing the parts on an enlarged scale;

Figure 3 is a fragmentary view taken in section on line 3-3 of Figure 1 and showing the means employed for constraining the upper tong to vertical movement in either transverse adjustment;

Figure 4 is a detail sectional view taken on line 4-4 of Figure 1;

Figure 5 is a sectional view taken on line 5-5 of Figure 1;

Figure 6 is a sectional view taken on line 6-6 of Figure 1;

Figure 7 is a fragmentary view partly in side elevation and partly in vertical section

and further illustrating the structure shown in Figure 6 and related parts;

Figure 8 is a view similar to Figure 7 but showing a modified construction; and

Figure 9 is a view in end elevation looking toward the right in Figure 1.

Referring to the drawings, and more particularly to Figure 1, the numeral 1 designates a knee of a sawmill carriage having a face 2 and a base 3. The base 3 is slidably mounted in the usual manner upon a head block 4 for transverse movement with respect to the log carriage. The transverse adjustment of the knee relative to the carriage may be effected from a set shaft 6 in any conventional or well known manner. For a full and complete disclosure of one means for effecting such transverse adjustment of the knee reference is made to our pending application, identified above.

Arms 11 and 12 are keyed to the ends of a rocker shaft 13 journaled in a bearing 14 which may be formed integrally with the base of knee 1, the upper ends of arms 11 and 12 receiving the ends of a shaft 15 which passes loosely through bearings 16 formed on the underside of the upper tong arm 17 whereby the rear end of the latter is pivotally connected to and supported by arms 11 and 12. Pins 18 and 19 are provided with reduced ends 20 which pass through tong arm 17 and with heads 21, the pins being held in position by means of nuts 22 threaded upon the ends thereof. Pins 18 and 19 are selectively adapted for sliding movement in a channel 23 formed by means of strips 24 and 25 arranged in parallel relation to each other and to the face of the knee 1 and secured by means of bolts 26 to a vertical member 27, member 27 being secured to one side of knee 1 by means of bolts 28. As shown in Fig. 3, the adjacent edges of strips 24 and 25 fit loosely between arm 17 and head 21 of pin 18 whereby the latter is held in position in channel 23 for sliding movement along the same. Pins 18 and 19 may be provided with collars 29 which loosely fit the pins and provide for a rolling action between the same and strips 24 and 25 upon movement of tong arm 17 in a vertical plane. The

100

respective upper ends 31 and 31' of strips 24 and 25 are beveled outwardly, as shown in Fig. 1, for the purpose hereinafter explained.

5 A shaft 32 is journaled in base 3 of knee 1 at the rear end thereof and provided with an eccentric 33 fixed thereto by means of a key 34, an eccentric sheave 35 having an arm 36 being arranged upon eccentric 33, as more 10 clearly shown in Fig. 7. A lever 37 comprising a collar 38 and arms 39 and 40 fixed thereto is pivotally mounted intermediate its ends on the rocker shaft 13 which extends loosely through collar 38, the lower end of arm 40 being bifurcated and pivotally connected to the end of arm 36 by means of a pin 41. Arm 12 is enlarged at the center thereof to form a frame 42 in which an apertured pin 43 is pivotally mounted, as more 15 clearly shown in Fig. 2, a bolt 44 passing through pin 43 and being pivotally connected at 45 to arm 39 of lever 37. A spring 46 is arranged upon bolt 44 and held slightly compressed between pin 43 and nuts 47 threaded upon the end of bolt 44. An adjustable bolt 48 is threaded into the end of arm 39 and engages the adjacent edge of arm 12 for the purpose hereinafter explained.

20 The rear end of the lower tong arm 49 fits into the lower bifurcated end of a hanger 50 having its upper end loosely mounted on rocker shaft 13 and is pivotally connected to the lower end of hanger 50 by means of a pin 51, hanger 50 thereby supporting the rear 25 end of tong arm 49. One end of a link 52 also fits into the lower bifurcated end of hanger 50 and is also pivotally connected thereto by means of pin 51, the other end of link 52 being loosely mounted on an eccentric or crank pin 53 fixed in a lug 54 which 30 may be formed integral with eccentric 33, this end of link 52 being held upon pin 53 by any suitable means such as a nut 55 threaded upon the end of the latter. Adjustable stops or bolts 56 and 57 are threaded 35 into lugs 58 which may be cast integrally with the base 3 of knee 1 and are arranged, as shown in Fig. 7, to engage the opposite sides of block 54 to limit rotary movement 40 of shaft 32 through an angle of 180° for the purpose hereinafter explained.

45 The forward end of tong arm 49 is slidably mounted in a shoe 59 provided with a pin 60 which is similar to pins 18 and 19 and is arranged in channel 23, as shown in Fig. 4, for sliding movement along the same. As more clearly shown in Figs. 1 and 5, shoe 59 is provided with a lug 61 arranged to engage with the head 62 of bolt 63 loosely mounted in lugs 64 and 65 cast integrally with member 27, a spring 66 being arranged on bolt 63 between lug 64 and a washer 67 held between a shoulder 68 in the bolt and a sleeve 69 fitted upon the latter and held in position by means of nuts 70 threaded upon

the end of the bolt. One edge of a plate 71, arranged upon bolt 63 as shown, fits against the adjacent face of knee 1 and is provided with an opening to receive a pin 72 fixed in head 62 of bolt 63, the engagement of plate 71 with knee 1 and its connection by means of pin 72 with the head of bolt 63 acting to hold the latter against rotary movement in lugs 64 and 65 whereby the head of the bolt and plate 71 associated therewith are always in the position shown in Fig. 5 for engagement with lug 61 of shoe 59, bolt 63 thereby acting as a stop to support the forward end of tong arm 49 when the latter is in its lowermost position, spring 66 being compressed upon engagement by lug 61 with plate 71 and thus acting as a cushion.

70 The mechanism for effecting movement of tong arms 17 and 49 in a vertical plane will now be described.

75 As shown in Fig. 1, this mechanism comprises a reversible electric motor 115, the stator of which is securely bolted to the upper tong 17 and the armature shaft 115' of which is connected by a coupling 109 to a worm shaft 103. The shaft 103 is journaled in bearings provided therefor in a casing 73 and has a worm 104 fixed thereto and meshing with a worm wheel 89 mounted on and having appropriate friction driving connection with a shaft 80 supported for rotation in bearings provided therefor on the casing 73 and tong arm 17. The casing 73 is securely bolted to the tong arm 17. A pinion 102 is fixed on shaft 80 and meshes with a rack 98 sliding through a guide 97 swiveled on the shaft 80 and having its lower end pivotally connected as at 128 to the lower tong arm 129.

80 For holding the tong arms in adjusted position when the motor 115 is turned off and especially for holding the upper tong arm elevated when the dog is idle, a snubbing brake is provided on the armature shaft 115' and consists of brake members 119 and 120 provided with friction faces 121 pivotally connected at their lower ends by means of a pin 122 to a bracket 123 secured to the upper tong arm 17. The brake members 119 and 120 have their friction faces held in engagement with a drum 112 keyed to the armature shaft 115' by virtue of the provision of a bolt 126 extending through apertured lugs on the brake members and having its head engaged with one apertured lug and having its other end provided with nuts 127 serving as an abutment for one end of a spring 125, the other end of the spring engaging the other of said lugs.

85 Assuming that the parts are in their respective positions as shown in Fig. 1, it will be seen from the foregoing description that upon operation of motor 115 in one direction the worm 104 through worm gear 89 will rotate shaft 80 and pinion 102 keyed thereto and that shaft 80 may thereby be 90

rotated in a clockwise direction, as viewed in Fig. 1, to cause pinion 102 to travel downwardly along rack 98 to effect downward movement of tong arm 17 in a vertical plane about shaft 15 as a center, pin 18 sliding downwardly along slot 23. The upper end of slot 23 is curved on the arc of a circle having shaft 15 as a center to permit arm 17 to move about the latter as a center during 10 sliding movement of pin 18 in the upper end of slot 23. Downward movement of pin 18 in slot 23 below the position of the pin shown in Fig. 1 will cause arm 12 to move forward slightly in a counter-clockwise direction 15 about shaft 13 as a center and spring 46 to be compressed between pin 43 and nuts 47. When tooth 130 engages log 132 tong arm 17 and pinion 102 carried thereby will be held against further downward movement. Upon 20 continued rotation of pinion 102, therefore, rack 98 will be drawn upwardly through housing 97 to pull lower tong arm 49 upwardly and cause the tooth 133 secured to the latter to be embedded in the underside of the log, 25 tong arm 49 being moved upwardly until the teeth 130 and 133 are embedded in the log with the same force, at which time worm gear 89 will slip completely with respect to shaft 80 by reason of its friction connection with 30 the latter.

When the sawyer observes that the tong arms have been moved together a sufficient amount to grip or hold the log, he shuts down motor 115. When the log is to be released, 35 motor 115 is reversed to move the tong arms 17 and 49 away from each other.

If it is desired to project teeth 130 and 133 a greater distance beyond the face of knee 1 to hold a comparatively large log, motor 115 40 is operated to move tong arm 17 upwardly until pin 18 is above the upper ends 31 and 31' of strips 24 and 25 and beyond channel 23 formed by the latter. Shaft 32 is then rotated by means hereinafter described in a 45 counter-clockwise direction, as viewed in Figs. 1 and 7, until block 54 engages stop 57, stop 57 being adjusted to permit rotation of shaft 32 through 180 degrees from the position thereof shown in Figs. 1 and 7. Lever 50 50 37 will thus be rotated in a counter-clockwise direction about rocker shaft 13 and cause bolt 48 to act against the adjacent edge of arm 12 to move tong arm 17 forward, the eccentricity of eccentric 33 and the relation between arms 55 39 and 40 of lever 37 being such that pin 19 is moved into alignment with slot 23 for sliding movement therein. At the same time, crank pin 53 will also move through 180° from the position thereof shown in Figs. 1 and 7, and thus cause tong arm 49 to slide in shoe 59 in a direction transverse to the face of knee 1, tooth 133 thereby being projected forward beyond the face of knee 1 a distance equal substantially to the throw of crank 60 pin 53, this distance being equal to the dis-

tance which tooth 130 is projected beyond the face of the knee, or in other words, the distance between pins 18 and 19. As shown in Fig. 1, the hanger 50 is angularly disposed to the right of the vertical through rocker shaft 13 so that during the movement of crank pin 53 in a counter-clockwise direction through the first 90°, pin 51 will move downwardly to compensate for the upward movement of pin 53. In this connection it will be 70 seen that if the rear end of lower tong arm 49 were connected directly to crank pin 53, as shown in the modified form in Fig. 8, the rear end of the tong arm would be moved upwardly with pin 53 and cause arm 49 to tilt 75 a considerable amount about pin 129 as a center. The parts are so arranged that when pin 53 reaches its uppermost position pin 51 is in its lowermost position. During movement of pin 53 in a counterclockwise direction 80 through the last 90°, therefore, the latter will move downwardly, but pin 51 will compensate for this movement by moving upwardly about shaft 13 as a center. By employing the hanger 50 and connecting the rear 85 end of tong arm 49 to crank pin 53 by means of link 52, therefore, rotary movement of tong arm 49 in a vertical plane about pin 129 as a center upon rotation of shaft 32 is minimized, arm 49 being thereby maintained in 90 substantially a horizontal plane during movement thereof in a direction transverse to the face of knee 1.

The upper tong arm 17 may be provided on the underside thereof with a stop 134 arranged to engage a rubber bumper 135 with which shoe 59 is provided when pin 18 is in slot 23 and with a stop 136 arranged to engage bumper 135 when pin 19 is in slot 23 to limit relative movement of the tong arms toward 100 each other. A pin 137 is slidably mounted in the upper end of member 27 and backed by a spring 138 arranged upon a bolt 139 secured to pin 137 and extending loosely through the upper portion 140 of member 27, nuts 141 being threaded upon the end of bolt 139 to limit downward movement of pin 137. A block 142 is secured to the upper side of tong arm 17 and arranged to engage pin 137, the latter thereby acting as a cushion and a stop 105 to limit upward movement of the tong arm. An arm 143 may be secured to member 27 by means of bolts 144 and arranged as shown in Figs. 1 and 9 to prevent movement of the forward end of tong arm 17 away from member 27 when either of the pins 18 and 19 are moved to a position above the upper ends 31 and 31' of strips 24 and 25 forming the channel 23, ends 31 and 31' being beveled outwardly, as explained above, to facilitate entrance 110 of pins 18 and 19 into channel 23. When the teeth 130 and 133 are extended to the fullest extent beyond the face of knee 1, in which position of the teeth pin 19 of upper tong dog 17 will be in channel 23 and 115

crank pin 53 will be in its extreme position to the left of the shaft 32 and block 54 against stop 57, the teeth may be receded by operating motor 115 to raise tong arm 17 and carry pin 19 above the upper end of channel 23. Shaft 32 is then rotated in a clockwise direction, as viewed in Figs. 1 and 7, which movement of shaft 32 will carry upper tong arm 17 backward a distance equal to the distance between pins 18 and 19 to place pin 18 in alignment with channel 23. Spring 46 is stiff enough so that upon movement of arm 39 to the right as viewed in Fig. 1, the spring will be only slightly compressed and act upon pin 43 to carry arm 12 and tong arm 17 connected thereto backward. This rotation of shaft 32 in a clockwise direction until block 54 engages stop 56 will also cause lower tong arm 49 to slide backward in shoe 59 a distance equal to the distance between pins 18 and 19 whereby teeth 130 and 133 are receded the same amount to the respective positions thereof shown in Fig. 1, in which position of the teeth the log is held to cut the thinnest board. The means for rotating shaft 32 in either direction will now be described. Referring more particularly to Fig. 2, a worm gear 145 is loosely mounted on a member 146 splined to shaft 32 and held in frictional engagement by friction discs 147 with a member 148 also splined on shaft 32, a spring 149 being held in compression between member 148 and adjustable nuts 150 threaded upon the end of shaft 32 to hold gear 145, friction discs 147 and members 146 and 148 in proper frictional engagement with each other. A suitable housing 151 for these friction elements may be arranged upon shaft 32, as shown, and closed by a plate 152 secured to the housing by bolts 153, the housing being provided with suitable bearings for a shaft 154 having a worm 155 arranged in mesh with worm gear 145. A reversible electric motor 156 is secured by means of bolts 157 to a bracket 158 secured, in turn, to knee 1 by means of bolts 159. The armature shaft of the motor 156 is connected to the worm shaft 154 to drive the same. Upon operation of motor 156 in a given direction shaft 32 will be rotated in a counter-clockwise direction to advance or extend teeth 130 and 133 further beyond the face of knee 1 until block 54 engages stop 56, as explained above, at which time worm gear 145 will slip completely with respect to shaft 32 to permit continued operation of motor 156. When the teeth have been advanced in this manner motor 156 is shut down. Upon reversal of motor 156 shaft 32 is rotated in a counter-clockwise direction to recede the teeth 130 and 133 to their respective positions as shown in Fig. 1, block 54 engaging stop 56 when the shaft has rotated through 180°, at which time worm gear 145 will again slip completely with respect to shaft 32 to permit continued operation of motor 156 which may

then be shut down. A cap 162 may be placed over the end of shaft 32 and secured to plate 152 by means of bolts 163.

As shown in Fig. 8, the rear end of the lower tong arm 189 to which the lower end of the rack 190 is pivotally connected by the pin 191 may be pivotally connected by the pin 192 to a lug 193 formed integrally with the eccentric 194, the latter being fixed on the operating shaft 195, corresponding to shaft 32 in Figs. 1 and 7, the lug 193 corresponding to the lug 54. It will therefore be seen that in the modification shown in Fig. 8 there has been omitted the hanger 50 and the link 52. The remaining parts shown in Fig. 8 are identical in construction and manner of operation as the corresponding parts shown in Fig. 1, and are designated by primed reference numerals similar to the reference numerals of the corresponding parts shown in Fig. 1.

The invention claimed is:

1. In a sawmill dog, a knee having a face and provided with a channel arranged parallel thereto, upper and lower log-holding arms associated with said knee and mounted for movement toward and away from each other and for movement transverse to the face of said knee, and means for effecting said movements of said arms, said mounting including a plurality of pins carried by one of said arms and adapted and arranged for movement in said channel, and means for selectively positioning said pins in said channel for movement therein whereby the position of said last-mentioned arm relative to said knee may be changed in a direction transverse to the face of the latter.

2. In a sawmill dog, a knee having a face and provided with a channel arranged parallel thereto, upper and lower log-holding arms associated with said knee and mounted for movement toward and away from each other and for movement transverse to the face of said knee, a plurality of pins carried by one of said arms and adapted and arranged for movement in said channel, means for selectively positioning said pins in said channel for movement therein whereby the position of said last-mentioned arm with respect to said knee may be changed in a direction transverse to the face of the latter, a shoe guided for movement parallel to the face of said knee and supporting the other of said arms for sliding movement with respect to said shoe, means for causing said sliding movement of said other arm whereby the position of the same with respect to said knee may be changed in a direction transverse to the face of the latter, and means for effecting said movement of said arms toward and away from each other.

3. In a sawmill dog, a knee having a face, upper and lower log-holding arms associated with said knee and mounted for movement

toward and away from each other and for movement transverse to the face of said knee, a lever pivotally mounted intermediate its ends to said knee and connected to one of 5 said arms, a shaft connected to said lever and to the other of said arms whereby the latter are moved forward and in a direction transverse to the face of said knee upon rotary movement of said shaft in a given 10 direction and are retracted upon a reverse movement of said shaft, means for causing said movements of said shaft, and means for effecting said movement of said arms toward and away from each other.

15 4. In a sawmill dog, a knee having a face, a log-holding arm associated with said knee and supported for vertical movement and for movement in a direction transverse to the knee face independently of said vertical 20 movement, an actuating member cooperable with the arm to positively move the same outwardly and a spring interposed between the actuating member and the arm to provide a yieldable connection between said actuating 25 member and the arm in respect of movement in an opposite direction.

5. In a sawmill dog, a knee having a guide-way along one side thereof, and a log-holding arm having spaced lateral projections 30 selectively engageable with said guide-way.

6. In a sawmill dog, a knee having a member disposed adjacent one side thereof and formed with a guide-way terminating adjacent the top of the knee, a log-holding arm 35 having a plurality of laterally projecting members selectively engageable with the guide-way, means for moving the log-holding arm vertically to move either of said laterally projecting members into or out of 40 the guide-way and means for moving the log-holding arm transversely of the knee to align any one of its laterally projecting members with the guide-way.

7. In a sawmill dog, a knee having a face, upper and lower log-holding arms, means for mounting the forward portions of the log-holding arms on the knee for movement toward and away from each other and for movement transverse to the knee face, a shaft 45 mounted on the knee, links between the shaft and the rearward end portion of the upper log-holding arm whereby to support the upper log-holding arm and permit the same to swing vertically and also move transversely to the knee face, means supported on the upper log-holding arm for moving the upper and lower log-holding arms toward and away from each other, said lower log-holding arm having means for supporting its rearward 55 end on said shaft and power means for moving the log-holding arms transversely of the knee face.

8. A power sawmill dog of the tong type comprising a knee having a face, upper and 60 lower elongated tongs, means coacting with

the forward portions of the tongs and with the knee for constraining the tongs to up and down movement toward and away from each other and for movement transverse to the knee face to project forwardly of said 70 face to greater or less distances, the space between said tongs forward of the knee being unobstructed so as to permit the work to engage the face of the knee in all positions of the tongs, a swingable supporting 75 and driving member mounted on the knee and pivotally connected to the rearward end of the upper tong at a substantial distance from the knee face, a motor, means actuated by the motor and cooperable with said sup- 80 porting and driving member for swinging the same to move the upper tong transversely relative to the knee face, means for supporting the rearward end of the lower tong at a point spaced vertically from the pivot of 85 the upper dog on its swingable support in such manner as to permit it to be moved transversely back and forth relative to the knee face and up and down toward and from the upper tong, means actuated from said 90 motor for moving the lower tong transversely back and forth relative to the knee face, and motor driven means for moving the upper and lower tongs toward and away from each other.

9. A power sawmill dog of the tong type comprising a knee having a face, upper and lower elongated tongs, means coacting with the forward portions of the tongs and with the knee for constraining the tongs to up and down movement toward and away from each other and for movement transverse to the knee face, a swingable supporting and driving member mounted on the knee and pivotally connected to the rearward end of 100 the upper tong at a substantial distance from the knee face, a motor, a lever operatively associated with said supporting and driving member, a shaft driven from the motor, an eccentric on the shaft operatively connected 105 with the lever, means actuated from the shaft for moving the lower tong transversely back and forth relative to the knee face, and motor driven means for moving the tongs up and down.

110 In witness whereof, we hereto affix our signatures.

ROSS E. LANGILL.
WILLIAM B. GRUETER.
